CLAIM

The ornamental design for a battery pack contact end, as shown and described.

DESCRIPTION

FIG. 1 is a perspective view of a battery pack contact end showing our design;

FIG. 2 is a side elevational view of the pack contact end shown in FIG. 1. In side elevation, the pack contact end is symmetrical about its longitudinal axis. All side elevational views of the pack contact end regardless of the line of sight are identical; and,
